UNITED STATES PATENT OFFICE

101,828

DESIGN FOR A CIRCULATING TYPE HEATER

Walter D. Teague, New York, N. Y., assignor to
American Gas Machine Company, Albert Lea,
Minn., a corporation of Delaware

Application June 1, 1936, Serial No. 62,913

Term of patent 7 years

To all whom it may concern:

Be it known that I, Walter D. Teague, a citizen of the United States, residing at New York city, in the Borough of Manhattan and State of New York, have invented a new, original, and ornamental Design for Circulating Type Heaters of which the following is a specification, reference being had to the accompanying drawing, forming a part thereof, wherein

Fig. 1 is a perspective view of a circulating type heater showing my new design;

Fig. 2 is a view in side elevation of the same on a reduced scale; and

Fig. 3 is a plan view of the same on a reduced scale.

I claim:—

The ornamental design for a circulating type heater substantially as shown and described.

WALTER D. TEAGUE.
